UNITED STATES PATENT OFFICE.

GRACE S. PUTNAM, OF NEW YORK, N. Y.

DOLL.

Application filed February 6, 1925. Serial No. 7,208.

This invention relates to dolls and particularly to that type thereof in which the body of the figure comprises an outer envelope of cloth, or other suitable material, stuffed with 5 any suitable soft padding or stuffing. The principal object of the invention is to provide a novel construction of great simplicity requiring a minimum amount of labor for the production of the finished figure, while 10 producing a figure which imitates with remarkable fidelity the shape and characteristic postures of an infant. Other objects will be apparent from the following more detailed description.

Reference is had to the accompanying drawings which illustrate an example of the invention without defining its limits and wherein Fig. 1 is a plan view of the front blank; Fig. 2 is a similar view of the rear 20 blank; Fig. 3 is a front view showing the first step in the assembling of the blanks; Fig. 4 is a front view of the assembled blanks; Figs. 5 and 6 are side and rear views of the assembled blanks in stuffed condition; 25 and Fig. 7 is a front view of the completed figure, with the head secured thereto.

The invention consists in the novel configuration, proportion, and assembly of the front and back fabric blanks which form the 30 envelope of the figure and define its shape, and which permit movement of the legs of the figure without necessitating making the legs separately from the body, as with the constructions heretofore employed.

In making the figure, I employ a front blank A and a rear blank B intended to be sewed along their marginal portions. The body portion of the front blank, as clearly shown in Fig. 3, is of smaller area than the 40 rear blank, while the lower portions of the legs 10, 11 of the two blanks are of substantially the same shape and size. As shown in Figs. 1 and 3, the front blank A is shaped to form a widened chest portion α and a reduced waist portion α' . The legs 10 of the front blank extend outwardly, then inwardly and are spaced apart along the line 12 which terminates at its ends at the points which correspond approximately with the 45 under part of the knees. The sides 13 of rear blank B curve outwardly from the top line 14 thereof to produce a wider portion extending a substantial distance above the line 15 between the leg portions 11 of the 50 blank. The lines 14 and 15 of the rear blank, if desired, may be made longer than the cor-

responding lines 16 and 12 of the front blank for a purpose which will presently be described. Any convenient registering marks as indicated at 17 are placed at spaced 60 points about the margin of the blanks to provide guiding means for insuring the proper assembling thereof.

In assembling the blanks, the top line 16 of the front blank is placed over the top line 14 of the rear blank with the indicating or registering marks 17 on said lines in alignment. The blanks are then sewed together from each mark 17 to the sides thereof leaving an unsewed portion between said marks. 70 If, as suggested above, the line 16 is shorter than the line 14 and the marks 17 are located an equal distance from the sides of each blank, the excess material of the rear blank will, in such case, cause a gaping opening 18 75 to be produced in which the head 19 of the doll is adapted to be inserted and secured in any suitable manner to the fabric of the blanks.

The side margins of the body and leg portions of the two blanks are then sewed together, care being taken to bring each indicating mark 17 of one blank in alignment with its corresponding mark of the other blank. The marks 17 are so located that it 80 becomes necessary to form a plurality of folds or pleats 20, 21, in the rear blank to bring all of the marks into registry. In sewing the sides of the blanks together, it is 85 preferable to form the two large pleats 20, 90 extending inwardly from the sides of the figure and the two smaller pleats 21 extending upwardly from the lines 12, 15, approximately at the places shown in the drawing. After the entire marginal edges of the 95 blanks, with the exception of the opening 18 left along the top, have been sewed up, the envelope formed is stuffed with any suitable soft stuffing such as cotton batting or the like. The excess or surplus of material in 100 the rear blank will cause the stuffed figure to assume the contour and posture shown in Figs. 5 to 7. The greater width and area of the lower portion of the rear blank causes the stuffing to force the legs of the figure to 105 assume the positions shown in Figs. 5 to 7 and as the leg portions of the blanks are cut to the bent shape shown, the figure automatically assumes the characteristic posture of an infant, with the legs bent and heels in 110 natural proximity to each other.

The surplus material provided by the

pleats 20, 21, allows the legs of the figure to be moved from their normal positions, the pressure of the stuffing upon the fabric of the blanks causing the legs to return normally to the positions shown in Figs. 5 to 7 inclusive. By constructing the figure in the manner described, the back of the figure will be fully rounded in an unbroken curve thereby producing a natural appearance, the surplus material of the pleats permitting movement of the legs without distorting the roundness of the back. Furthermore there are no objectionable breaks or fissures such as are formed when the legs are separately attached as with the constructions heretofore employed. In addition, the stuffing causes the head and legs of the figure to be thrown forward to create a cuddling posture of great attractiveness which invites one to hold or caress the figure. The soft stuffing enhances the natural appeal due to the posture, as when the figure is held in the arms the soft feeling thereof is quite similar to that of a human infant. Finally the manufacture and assembling of the figure is of the utmost simplicity and the completed figure is of great durability.

While it is preferable to arrange the pleats 20, 21 as shown, it will be understood that the location as well as the number of pleats may be varied without departing from the principles of construction herein disclosed. It will also be understood that numerous variations, modifications and changes from the example herein illustrated may be resorted to without departing from the spirit of my invention.

I claim:

- 40 1. A figure of the character described comprising an outer envelope filled with stuffing, said envelope consisting of a front blank and a rear blank secured together along their marginal portions, said blanks each having a body portion and leg portions the leg portions of each of said blanks extending laterally at an angle from the body portion thereof to a point corresponding to the knee of the figure, and then being inclined inwardly from said point to bring the heels of said figure into closely spaced relationship, and said rear blank being of considerably greater width and length than said front blank whereby when said stuffing is inserted into said envelope the leg portions thereof will be forced by said stuffing upwardly and inwardly to cause them to assume normally an upwardly drawn, bent position resembling a characteristic posture of an infant.
- 60 65 2. A figure of the character described, comprising an outer envelope consisting of a front blank and a rear blank secured together along their marginal portions, said blanks each having a body portion and leg portions, the leg portions of each of said

blanks extending laterally at an angle to said body portion and then inwardly, and the body portion of said rear blank being sufficiently greater in width and length than said front blank adjacent to the leg portions thereof to form the back, the sides and curved buttock when said envelope is filled with the stuffing material whereby the leg portions will be forced by said stuffing to assume normally an upwardly drawn, bent position.

3. A figure of the character described comprising an outer envelope filled with stuffing, said envelope consisting of a front blank and a rear blank secured together along their marginal portions, said blanks each having a body portion and leg portions, the lower leg portions of said blanks below the knees being of substantially the same shape and size, and converging from the knees toward the feet, and the body and upper leg portions of said blanks being markedly dissimilar in shape and size, with said rear blank being of considerably greater width than said front blank adjacent to said leg portions and of considerably greater length, thereby to form a pendulous pocket which, when filled with the stuffing material, will form a rounded buttock from which the leg portions of said figure will extend upwardly in a drawn, bent position due to the pressure of said stuffing and the tension of the material of the shorter front blank.

4. A figure of the character described comprising an outer envelope consisting of a rear blank and a front blank, said blanks each having a body portion and leg portions, the body portion of said rear blank being of greater area than the body portion of said front blank and said blanks being secured along their marginal portions with the surplus material of the body portion of said rear blank arranged to form a plurality of inwardly extending pleats, certain of said pleats being arranged at the upper ends of said leg portions to provide a surplus of material which will permit movement of said leg portions; and a stuffing inserted between said front and rear blanks.

5. A figure of the character described comprising an outer envelope consisting of a rear blank and a front blank, said blanks each having a body portion and leg portions, the body portion of said rear blank being of greater area than the body portion of said front blank and said blanks being secured along their marginal portions with the surplus material of the body portion of said rear blank arranged to form a plurality of inwardly extending pleats; and a stuffing inserted between said front and rear blanks, the leg portions of said blanks being cut to form a bent shape and the pressure of said stuffing upon said blanks caus-

ing said leg portions to assume normally an upwardly drawn bent position to resemble the posture of an infant.

6. A figure of the character described comprising an outer envelope consisting of a rear blank and a front blank, said blanks each having a body portion and leg portions, the body portion of said rear blank being of greater area than the body portion of said 10 front blank and said blanks being secured along their marginal portions with the surplus material of the body portion of said rear blank arranged to form a plurality of inwardly extending pleats; and a stuffing 15 inserted between said front and rear blanks, the leg portions of said blanks being cut to form a bent shape and the pressure of said stuffing upon said blanks causing said leg portions to assume normally an upwardly 20 drawn bent position to resemble the posture of an infant, and certain of said pleats being arranged adjacent to the upper part of said leg portions to provide a surplus of

material which will permit movement of the legs from said bent position.

7. A figure of the class described comprising an outer envelope consisting of a rear blank and a front blank, said blanks each having a body portion and leg portions, the body portion of said rear blank being of greater length and width than said front blank, and of greater width in its lower part than in its upper part, said blanks being secured together along their marginal portions, with portions of the surplus material of said lower part of said rear blank arranged to form a plurality of inwardly extending pleats, and stuffing inserted between said blanks, the remainder of said surplus material of said rear blank causing the lower rear body portion of the figure to assume the shape of an infant's body.

In testimony whereof I have hereunto set my hand.

GRACE S. PUTNAM.
